UNITED STATES PATENT OFFICE.

EDWARD SNICKERS, OF MATLOCK, WASHINGTON.

AUTOMATIC GATE.

1,267,134.

Specification of Letters Patent. Patented May 21, 1918.

Application filed August 14, 1917. Serial No. 186,137.

To all whom it may concern:

Be it known that I, EDWARD SNICKERS, a citizen of the United States, residing at Matlock, in the county of Mason and State of Washington, have invented certain new and useful Improvements in Automatic Gates; and I do hereby declare the following to be a full, clear, and exact description of the invention, such as will enable others skilled in the art to which it appertains to make and use the same.

This invention relates to improvements in an automatic gate especially adapted for use in connection with scales for the purpose of preventing an unauthorized person from using the scale whenever desired.

Another object of this invention is the provision of a gate normally disposed over the scale and which is capable of being rendered inoperative when in this position to prevent the use of the scale.

A further object of this invention is the provision of a means for automatically opening the gate upon the arrival of a vehicle or the like on the scale.

A still further object of this invention is the provision of an automatic gate of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a front elevation of an automatic gate constructed in accordance with my invention,

Fig. 2 is a fragmentary perspective view of the same, illustrating the location of the gate with respect to the scale,

Fig. 3 is a longitudinal sectional view of the scale,

Fig. 4 is a fragmentary detail sectional view illustrating the means for automatically returning the gate to a closed position,

Fig. 5 is a detail sectional view taken on the line 5—5 of Fig. 4, 55

Fig. 6 is a perspective view of the means for locking the gate in a closed position,

Fig. 7 is a fragmentary sectional view of the means for swinging the gate in an open position and adapted to be actuated by the scale,

Fig. 8 is a detail sectional view illustrating the locking means applied to the scale,

Referring in detail to the drawings, the numeral 1 indicates as an entirety, a scale 65

consisting of a platform, which has secured thereto, a plurality of downwardly depending supporting rods or bolts 3, which have mounted thereon, coiled springs 4. The platform 2 is positioned within a casing 5, 70

which is embedded in the ground as shown in Figs. 1 and 2. The casing 5 has secured thereto, a plurality of transverse strips 6, that are provided with apertures to slidably receive the lower ends of the supporting rods 75

3 and on which the lower ends of the coiled springs 4 bear to support the platform 2 in an elevated position. The platform 2 has secured to each corner thereof, guide plates 7 that

engage within the side walls of the casing 5 80 to prevent the platform 2 from becoming displaced within the casing 5. The casing 5 is provided with an opening in one side thereof in which is positioned, a substantially U-shaped housing 8 in cross section. 85

The substantially U-shape housing 8 is secured to the platform 2 and to the under surface thereof in any suitable manner and is adapted to receive a gate actuating means, which will be hereinafter more fully described. 90

A supporting post 9 is positioned in the ground along one side of the scale 1 and at a point intermediate its ends and has secured thereto, a pair of plates 10, which support a gate supporting post or member 11. 95

The member 11 is provided with reduced portions 12 adjacent its ends on which are formed, spirals 13. A gate 14 of substantially rectangular formation has formed on one end thereof, extensions 15 that are recessed to receive arms 16 that are provided with a plurality of apertures. Cylindrical members 17 surround the reduced portions 12 of the supporting post or member 11 and 100 have formed thereon, extensions 18 that re-

ceive the extensions 15 of the gate 14 and overlie the arms 16. Extensions 18 are provided with apertures which aline with apertures in the arms 16 and with apertures in the extensions 15 to receive bolts whereby the arms and extensions 18 are secured to the extensions 15 of the gate 14. When the gate is in its normal position or overlying the scale, as shown in Fig. 2, the arms 16 are received within notches 19 formed in the gate supporting post or member 11. Rollers 20 are journaled to the arms 16 and ride upon the spirals 13 when the gate is swung to an open position so that the gate 15 will return to its normal position or closed position under its own weight. Projections 21 are formed upon the lower end of the supporting post or member 11, which support the lower cylindrical member 17 upon the gate when the gate is in a closed position. These stops or projections 21 limit the movement of the gate to a closed position. An arm 22 is provided with a reduced extension 23 which extends through an aperture in the lower edge of the gate 14 and receives a nut 24, whereby the arm 22 is rotatably connected to the gate. The arm 22 has its other end enlarged to form a journal 25 to receive a reduced extension 26 formed upon a substantially L-shaped member 27. The substantially L-shaped member 27 has formed thereon, a collar 28, which supports the bearing 25 upon the arm 22. A nut 29 is threaded to the reduced extension 26 after being passed through the journal 25. A lever 30 is pivoted to the other end of the substantially L-shaped arm 27 by a pin and slot connection and has its free end disposed within the substantially U-shaped member 8 of the scale 1, as clearly shown in Fig. 7.

A plate 31 is secured to the casing 5 of the scale 1 adjacent the opening in the casing and has formed thereon, eyelets 32 to rotatably receive a rod 33. The rod 33 has formed thereon, a handle 34, which is disposed exteriorly of the casing 5 for the purpose of rotating the rod 33 within the eyelets 32. The rod 33 is provided with an offset portion 35, which is disposed transversely of the opening in the scale or casing 5 and has journaled thereon, the lever 30. The lever 30 has secured to its inner end, an upwardly directed member 36, which has its free end disposed against the substantially U-shaped member 8, which is secured to the under face of the platform 2 of the scale 1.

A coiled spring 37 is secured to the substantially L-shaped member 27 adjacent the collar 28 and to the lever 30 as shown at 38.

In operation, when it is desired to render the gate inoperative or from being swung to an open position, the offset portion 35 of the rod 33 is swung downwardly so as to move the member 36 upon the lever 30 from engagement with the member 8 on the plat-

form 2, so that when a vehicle moves onto the platform on one end thereof, the platform will not rock the lever 30 upon its pivot, owing to that fact that the member 36 is disposed at such a point that the platform 2 will not engage the same when moved downwardly under the influence of the weight of the vehicle, thus preventing the vehicle from moving entirely onto the platform 2 of the scale 1. When it is desired to permit the gate to automatically open upon a vehicle moving onto the platform 2, the offset portion 35 of the rod 33 is disposed upwardly so as to position the member 36 into engagement with the substantially U-shaped member 8 carried by the platform 2, and as the platform 2 moves downwardly under the influence of the weight of the vehicle, the lever 30 is rocked upon its pivot to cause an upward movement of the arm 22, which moves the gate upwardly and upon further movement, the gate swings to an open position, owing to the rollers 20 traveling upon the spirals 13. The gate will maintain this open position until the vehicle moves off of the platform 2, permitting the platform to return to its normal position. As the platform 2 moves to its normal position, the rollers resting upon the upper ends of the spirals will move downwardly thereon, causing the gate to move to a closed position.

While I have shown and described the preferred embodiment of my invention, it will be understood that minor changes in construction, combination and arrangement of parts may be made without departing from the spirit and scope of the invention as claimed.

What I claim is:

1. An automatic gate comprising a scale, a post located adjacent said scale, a gate hinged to said post, means connecting the gate to the scale to cause said gate to move in an open position upon movement of the said scale, and means rendering said gate inoperative upon movement of the scale.

2. An automatic gate comprising a platform, a post located adjacent said platform, a supporting member carried by said post and having reduced portions, spirals formed on said reduced portions, cylindrical members surrounding the reduced portions, a gate secured to said cylindrical members, rollers carried by said gate and adapted to engage the spirals, and means connecting the gate to the scale.

3. An automatic gate comprising a casing, a spring supported platform located in said casing, a post located adjacent said casing, a member carried by said post, a gate hinged to said member, a spiral formed on said member, rollers carried by said gate and engaging the spiral, a rod rotatably mounted in said casing, an offset portion formed on

said rod, a lever pivoted on the offset portion having one end disposed against the platform, an L-shaped member pivoted and slidably connected to the other end of the lever, an arm journaled on said L-shaped member, and rotatably connected to the gate for causing said gate to move to an open position upon movement of the platform, and a handle secured to said rod for 10 rotating said offset portion downwardly to

disengage the lever from the platform to render the gate inoperative by the movement of the platform.

In testimony whereof I affix my signature in presence of two witnesses.

EDWARD SNICKERS.
